bling of the two small plates 7, 8 while allowing the freedom of movement required for their relative transverse displacement in opposite directions. Moreover, this interfitting arrangement will guide the plates during their relative movements.

The ends 22d of the mortise-carrying projection are thicker than and project from the inner face of the projection to engage the corresponding edge of the slide rule. The same applies on the other side to the ends 23d of the mortise-carrying projection 23b. When these thicker end portions 22d or 23d of the mortise-carrying projections engage the edges of the slide rule the two ribs 14a, 15a are positioned by construction in the middle of the guide grooves 17a, 18a so that they do not contact the upper and lower walls thereof. On the other hand, the depth of these ribs 14a, 15a is calculated to prevent them from contacting the bottom walls of the grooves 17a, 18a. Thus, in the inoperative or uncoupled position shown in Figs. 3 and 4 the ribs 14a, 15a do not contact the slide 3 and the latter cannot be carried along by the running during its longitudinal movements along the slide rule.

The small plates 7, 8 are held in this position by suitably shaped leaf springs 24a, 24b. The spring 24a urges the tenon-shaped projection 23a of plate 8 in the direction of the arrow f_1 , thereby pressing the thicker ends 23d of its opposite mortise-carrying projection 23b against the registering edges of the slide rule. Similarly, the spring 24b urges the tenon-shaped portion 22b of plate 7 in the direction of the arrow f_2 , thereby pressing the thicker ends 22d of its opposite projection 22a against the other edge of the slide rule. Each spring is adapted to react with its end portions against the corresponding edges of the slide rule, as shown. Besides, these springs 24a, 24b are housed in the free space available between the thicker end portions 22d, 23d of the mortise-carrying projections 22a, 23b respectively.

Figures 3 and 4 of the attached drawings illustrate the component elements of the runner in their normal positions as described hereinabove. In this position it is possible to move the runner along the slide rule without carrying along the slide 3 since the ribs 14a and 15a are located in the middle of the grooves 17a, 18a and do not contact the walls thereof. Thus, the runner is guided with all the desired efficiency and accuracy during its movements, due to the sliding engagement provided between the thicker ends 22d, 23d of the mortise-carrying projections 22a, 23b and the relevant edges of the slide rule.

When it is desired to drivingly connect or couple the runner with the slide 3 this may be obtained by simply exerting with the fingers two pressures of opposite directions as illustrated by the arrows F_1 , F_2 against the upper and lower edges 8a, 7b respectively of the plates 8, 7 (Figs. 5 and 6). In fact, the pressure exerted in the direction of the arrow F_2 on the edge 7b of plate 7 will press the rib 14a against the opposite wall of the groove 17a of slide 3. Similarly, the pressure exerted in the direction F_1 on the edge 8a of plate 8 will press the rib 15a against the opposite wall of the groove 18a. As a result, a wedging action takes place between the ribs and the slide 3 and the latter is drivingly connected with the runner. Consequently, under these conditions the slide 3 may be moved bodily with the runner, provided of course that the pressures F_1 , F_2 are maintained. At the same time, the slight transverse relative displacement of the plates 7, 8 in opposite directions has caused the tenon-shaped projections 23a, 22b to move somewhat out from the mortise-carrying projections 22a, 23b, as the springs 24a, 24b are flattened.

Figures 7 to 9 of the drawings illustrate another typical embodiment of the slide rule of this invention. This modified embodiment is based on the same principle as the preceding embodiment but in this case no grooves are formed in the slide 3. The ribs or fins 14, 15 of plates 7, 8 engage a pair of grooves formed by widened portions

of the intervals provided beforehand between the fixed bars 1 and 2, and the movable slide 3.

More particularly, the ribs 14 of plate 7 engage the groove 16 formed by a widened portion of the interval between the fixed bar 1 and the slide 3, said widened portion being provided on the side of plate 7. The ribs 15 of plate 8 engage the groove 17 positioned on the other face of the slide rule and symmetrically to the groove 16 with respect to the longitudinal median line of the slide rule. This groove 17 consists of a widened portion of the interval formed between the bar 2 and the movable slide 3, this widened portion being provided on the side of the plate 8. Thus, the ribs 14, 15 are located on either sides of the slide 3.

The plates 7, 8 are interconnected along their corresponding edges by resilient strips 9, 10 engaging the registering edges of the slide rule so that these strips urge the plates 7, 8 of the runner in the direction of the arrows f_1 and f_2 respectively.

Thus, the ribs 14 of plate 7 are pressed against the fixed bar 1 and the ribs 15 of plate 8 are pressed against the fixed bar 2 (see Fig. 8). Consequently, the runner may be moved along the rule without carrying along the slide 3. Moreover, the runner is properly guided along the slide rule by the engagement between the ribs 14, 15 and bars 1, 2 respectively.

The driving connection between the runner and the slide 3 may be obtained by simply exerting a moderate pressure in opposite directions, as indicated by the arrows F_1 , F_2 , against the edge 7b of plate 7 and against the edge 8a of plate 8 respectively, these opposite pressures producing a moderate relative displacement of both plates until the ribs 14 of plate 7 and ribs 15 of plate 8 engage the corresponding edges of the slide 3 (Fig. 9). Thus, the slide is somewhat clamped between the ribs 14, 15 and drivingly connected with the runner. As a consequence, the runner may be moved bodily with the slide, but when the aforesaid pressures F_1 and F_2 are released, the resilient strips 9, 10 will immediately restore the plates 7, 8 to their initial positions in which they permit the movements of the slide independently of the runner.

The slide rule according to this invention is particularly advantageous since the operator may, by performing a very simple movement, couple the runner with the middle slide so as to displace them bodily, thereby simplifying considerably the problems to be performed therewith.

What I claim is:

1. Slide rule comprising two fixed bars rigid with each other, a movable slide slidably mounted between said bars, a pair of plates disposed on either sides of the slide rule and constituting the runner thereof, assembling means between said plates for fastening the latter in the longitudinal direction while permitting a limited relative movement thereof in the transverse direction, at least two longitudinal guide grooves in the slide rule, at least one side wall of each groove being formed on the movable slide, one of said grooves being formed on one face of the slide rule and the other groove on the other face, ribs rigid with the inner faces of said plates and projecting into said groove, resilient means bearing on said fixed bars and urging said plates, whereby the ribs of said plate will not contact the walls of said movable slide when said plates are not moved in the transverse direction.

2. Slide rule according to claim 1, wherein said plate-urging resilient means consist of a pair of curved metal strips mounted along the edges of said fixed bars and bearing thereon to urge said plate.

3. Slide rule according to claim 1, wherein said longitudinal guide grooves are formed in one face of said movable slide and in the other face of said movable slide.

4. Slide rule according to claim 1, wherein each plate of said runner comprises on an edge parallel to the

slide rule a tenon projecting at right angles to the general plane of the rule and on the opposite edge another projection formed with a mortise corresponding in shape to said tenon, said tenon and mortise arrangement of one plate being reversed on the other plate, the tenon of each plate engaging the mortise in the projection of the other plate.

5. Slide rule according to claim 4, wherein the projection perpendicular to each plate and wherein a mortise is formed comprises at either ends an inwardly-projecting extension adapted in the inoperative condition to engage the edge of the relevant fixed bar of the slide rule, the length of said extensions being calculated to prevent said plate ribs from contacting the movable slide. 10

6. Slide rule according to claim 1, wherein said two longitudinal guide grooves consist of two widened portions of the intervals provided beforehand between the fixed bars and the movable slide, said guide grooves being located on opposite faces and in the vicinity of longitudinal opposite edges of the slide rule.
